INVENTOR
RICHARD M. SWANSON
BY HIS ATTORNEYS

William Beck Williamson

UNITED STATES PATENT OFFICE.

RICHARD M. SWANSON, OF MINNEAPOLIS, MINNESOTA.

SIFTER FOR ASHES IN FURNACES.

Application filed June 12, 1925. Serial No. 36,862

This invention relates to a sifting device, and particularly to an ash sifter adapted to be disposed in a furnace under the grate bars thereof. As is well known, it is desirable in most cases to sift the ashes passing through the grate bars of a furnace in order to save the unburned fuel. This sifting operation is usually a very inconvenient, dusty and unwelcome task and many furnace operators, especially those operating domestic furnaces, waste the unburned fuel rather than go to the inconvenience of sifting the ashes.

It is an object of this invention, therefore, to provide a simple and efficient ash sifter adapted to be disposed in a furnace and which will be operated in the furnace so that all dust and dirt will be retained in the furnace and yet the unburned fuel can be readily separated from the ashes.

It is a further object of the invention to provide such a device comprising a support adapted to be disposed in the bottom of the furnace and extend about the walls thereof, together with a screen carried on said support and mounted for reciprocating movement, said screen preferably being connected to the grate bars in such a way that when the grate bars are moved to shake down the ashes the screen will be reciprocated.

It is more specifically an object of the invention to provide an ash sifter comprising a bar bent to extend around the sides and rear of the furnace, which bar has another bar upstanding therefrom and extending across the furnace on which a flat screen is supported and pivoted about a vertical axis, which screen extends beneath the grate bars of a furnace and inclines forwardly and downwardly, the front edge of said screen being connected to bars rigidly secured to the grate bars at the front end so that the screen will be reciprocated when the grate bars are moved, means also being provided to hold the front edge of the screen in elevated position.

These and other objects and advantages of the invention will be fully set forth in the following description made in connection with the accompanying drawings in which like reference characters refer to the same parts throughout the different views, and in which,

Fig. 1 is a view in central vertical section through the lower part of a domestic furnace, with the invention therein;

Fig. 2 is a top plan view of the sifting device; and

Fig. 3 is a vertical section taken on the line 3—3 of Fig. 1, as indicated by the arrow.

Referring to the drawings, a portion of a furnace of the domestic type is illustrated, of which it will only be necessary to consider the base 4, the lower wall 5 which surrounds the ash pit and which carries at its front a hinged ash door 6 and which has bearings 5^a in which are rotatably mounted the grate bars 7, said bars having rods 7^a projecting at their front adapted to receive a crank or operating member which will be inserted through the front of the furnace wall. The upper part or wall 8 of the furnace forming the combustion chamber is shown in part.

In accordance with the present invention, a screen support is provided and while various supports may be used, in the embodiment of the invention illustrated, a support is shown comprising a flat bar 10 which is bent into a U-shape and is adapted to extend along the sides of the furnace wall and around the semi-cylindrical rear portion thereof. There is often a ledge or offset in the wall of the furnace adjacent the bottom and said bar 10 conveniently fits therein. The bar, as shown, is disposed with its flat sides vertical and has a U-shaped member 11 secured thereto at opposite sides and has a flat substantially horizontal portion extending across the furnace above the floor thereof. The member 11 preferably is formed in two pieces, the ends overlapping at the central top portion thereof, said ends being provided with a plurality of holes 11^a through an alining pair of which a headed bolt 12 is adapted to pass which, preferably, will be equipped with a clamping nut 13 holding the overlapping ends of the portions of member 11 together. A flat screen 14 is provided, preferably, having substantially parallel side portions and a semi-circular rear portion so as to extend substantially parallel to the side walls of the furnace and beneath the grate bars thereof. The screen 14 is shown as connected to the horizontal flange of an angle bar 15 bent to extend around the sides and rear thereof, the forward edge of the screen being secured to a flat bar 16 extending between the ends of the angle bar 15. The screen preferably is additionally supported by a transverse bar

105
110
115

17 extending between the sides of the angle bar 15 and the screen is also provided with a central flat bar 18 which extends longitudinally and centrally therebeneath. The bar 18 is provided with a hole adapted to pass over and surround the upper end of the bolt 12 so that the screen is supported on the member 11 about a vertical axis. It will be noted that the sides of the screen are spaced from the wall of the furnace so that considerable lateral reciprocation of the screen and its frame is possible. A pair of flexible members shown as chains 19 are provided having their ends attached at spaced points at the front of the screen, preferably to the bar 16 and these chains are engaged at their upper central portions over hooks 20^a secured to bars 20, which latter bars have their upper ends bent around the rod 7^a of the grate bars and rigidly clamped thereto by headed and nutted bolts 21. A rod 22 is provided which extends over and downwardly at each side of the rods 7^a and has a depressed central U-shaped portion depending between said rods 7^a. The end of the bar 18 is formed as a hook 18^a and this hook is adapted to be engaged in the depressed central portion of the rod 22.

A pan 23 is provided adapted to be seated in the forward part of the ash pit immediately inside the front wall, which pan has a short flange or wall at its front edge and one side edge thereof and is provided with a pair of bail handles 24 and 25 disposed at one end and the front central portion thereof, respectively. The inner edge of the pan is flat and extends a short distance under the forward edge of the screen 14 and one end of the pan is also flat or unobstructed and the pan can be held by the handles 24 and 25 and used as a scuttle so that the material therein can be thrown out at one end thereof.

In operation, the screen or sifter device will be disposed in a furnace, as shown and described. The parts are such that the same can be inserted at the front of the furnace and attached to the standard parts thereof. The front edge of the screen normally is spaced a short distance above the bottom of the furnace. When the operator rotates the rod 7^a shaking the grate bars for the purpose of shaking down the ashes, the bars 20 will be oscillated and, owing to the connection of these bars and the screen through the chains 19, said screen will be laterally reciprocated about the bolt 12. The ashes and unburned fuel dropping from the grate bars onto the screen 14 will thus be sifted by said screen and the parts too large to pass through the screen will pass downward and off the front end thereof and into the pan 23. When said pan becomes full the same can be removed through the ash door and the contents of the pan can conveniently be

thrown or discharged into the furnace fire door. The screen 14 can be raised to engage the hook 18^a on the rod 22 to hold the front end of the screen in elevated position when it is desired to shovel the ashes from the ash pit. It will be noted that the bottom of the furnace is substantially unobstructed and the ashes can be shoveled out as usual. If desired, the ash pan 23 may be omitted. The material not passing through the screen will then be collected at the front of the furnace and this material can be shoveled up before the ashes beneath the screen are removed. 70 75

From the above description it is seen that applicant has provided a very simple and efficient ash sifter adapted to be disposed in a furnace. The sifter is operated and the ashes are sifted without substantially any additional effort in operating the furnace. This sifting takes place when the grate bars are operated to shake down the furnace. All dust is retained in the furnace and will quickly settle or be carried off by the draft. The sifted ashes can be removed as usual and the unburned fuel can conveniently be saved. The device can be installed in practically all standard types of furnaces and the same is easily and inexpensively produced. The device has been amply demonstrated in actual practice and found to be very successful and efficient. 80 85 90 95

It will, of course, be understood, that various changes may be made in the form, details, arrangement and proportions of the parts without departing from the scope of applicant's invention, which, generally stated, consists in a device capable of carrying out the objects above set forth, in the novel parts and combinations of parts disclosed and defined in the appended claims. 100 105

What is claimed is:

1. An ash sifter for a furnace having in combination, a support disposed in the furnace beneath the grate bars, a screen mounted thereon for reciprocating movement, and means constituting both a supporting and reciprocating means connected to one end of said screen and detachably secured to said grate bars adapted to reciprocate said screen when said grate bars are moved for discharging ashes said screen normally inclining downwardly toward the front end of said furnace to discharge coarse material. 110 115 120

2. An ash sifter for a furnace having in combination, a support disposed in the furnace beneath the grate bars and extending around the rear and sides of the furnace wall, a U-shaped bar upstanding therefrom, a flat sifter supported on said U-shaped bar for lateral movement, said screen having substantially the form of said furnace wall and having a front edge spaced from the front of said furnace and normally spaced above the bottom of said furnace, 125 130

and means suspending said screen from the grate bars including rigid members rigidly connected to the grate bars and adapted to reciprocate said screen when said grate bars are moved to discharge ashes.

3. The structure set forth in claim 1, said screen also being vertically movable about a transverse horizontal axis and normally inclining downwardly toward its front edge, 10 said edge being normally slightly spaced above the bottom of the furnace, and a support for holding said screen in position with its front end elevated.

4. An ash sifter for a furnace having in 15 combination, a support disposed in the furnace beneath the grate bars, a screen supported thereon for oscillating movement about a substantially vertical axis, means detachably connected to the grate bars and

connected to said screen for supporting and 20 oscillating said screen.

5. An ash sifter for a furnace having in combination, a bar bent to extend around the sides and rear of the interior wall of a furnace at the bottom thereof, a supporting bar 25 upstanding from the sides of said bar and extending across the furnace, a flat screen extending beneath the grate bars of said furnace, supported on said last mentioned bar and pivoted thereto about a vertical axis, 30 flexible members connected to said screen, rigid bars connected to said flexible members and rigidly connected to said grate bars whereby when said grate bars are moved for shaking ashes, said screen will be laterally reciprocated. 35

In testimony whereof I affix my signature.

RICHARD M. SWANSON.
